UNITED STATES PATENT OFFICE

GLENN A. HIGBEE, OF DETROIT, MICHIGAN

WINDOW-SHADE PULL

Application filed August 24, 1928. Serial No. 301,731.

This invention relates to fasteners, and particularly to fasteners for attaching pull cords to window shades.

An object of the invention is to provide a fastener for securing to a window shade (or other support) a pull cord (or other cord) and to adapt said fastener to be very quickly attached, to withstand a heavy pull, to be inexpensively manufactured, and to present

10 a neat and attractive appearance.

Another object is to provide a fastener comprising a member insertable in the reinforcing stick of a window shade (or in some other suitable support) and directly engageable by 15 the pull cord of the shade (or by some other supported element) and further comprising a cap adapted to conceal said member and adapted to distribute to the shade stick or other support such stresses as are imposed 20 upon said member in use.

Still another object is to resiliently connect such a cap to the member which it conceals so that the cap may be temporarily sprung out from the surface on which it seats 25 to permit ready engagement or disengagement of a cord with or from said member.

These and various other objects the invention attains by the construction herein-after described and illustrated in the accompanying drawings, wherein:

Fig. 1 is a fragmentary elevational view of the lower portion of a window shade equipped with the herein disclosed pull cord fastener.

Fig. 2 is a vertical sectional view of the same on line 2-2 of Fig. 1.

Fig. 3 is a side elevational view of an alternative construction, showing how the same may be tilted to facilitate engagement or disengagement of a cord beneath the cap of said fastener.

Fig. 4 is a vertical sectional view of the same.

Fig. 5 is a horizontal sectional view of the same.

Fig. 6 is a rear view of a dished cap employed in the alternative construction.

Fig. 7 is a plan view of a sheet metal blank from which is to be formed the cap of another 50 modification of the fastener.

Fig. 8 is an edge view of said blank showing a screw riveted thereto.

Fig. 9 shows the blank pressed to a dished form, adapting it to fit over the headed end portion of the screw.

Fig. 10 is a vertical sectional view of a fastener formed as illustrated in Figs. 7, 8 and 9, engaged with a window shade.

In the construction shown in Figs. 1 and 2, the reference character 1 designates an ordinary window shade having at its bottom edge the usual hem 2 receiving a reinforcing strip 3, formed usually of wood. A screw 4 is passed through one side of said hem and threaded into the strip 3, and a doubled pull cord 5 is looped around the shank of said screw. The latter rigidly carries a dished head or cap 6 preferably sheet metal, which seats through the hem 2 against the strip 3. A marginal notch 8 in said head opens downwardly to accommodate the doubled cord, when the fastener is in use.

The described fastener may be very quickly installed by looping the pull cord about the screw shank, passing said cord through the notch 8, and then using the free end portion of the cord to rotate the fastener while pressing the latter against the strip 3.

The head or cap 6 conceals the connection between the pull cord and screw and may, if desired, be ornamentally designed and finished to present a pleasing and attractive appearance. Said head furthermore powerfully resists any yielding of the screw responsive to a downward pull exerted upon the cord 5, since said head seats upon the hem sufficiently distant from the screw shank to strongly maintain the screw in its proper substantially perpendicular relation to the surface through which the screw enters the strip 5.

In case it proves desirable to shorten the pull cord by intermediately forming a knot therein and cutting off the looped portion above said knot, the chamber formed within the head 6 is adequate to accommodate such a knot.

In the modification shown in Figs. 3 to 6 inclusive a pull cord 9 is attached to the reinforcing strip 10 of a window shade 11 by 100

looping the upper end of the doubled cord about a screw 12 threaded into said strip. This construction again employs a dished head or cap 13 formed preferably of sheet metal but spring-connected to the screw 12 instead of rigidly carried by the latter as in the first-described construction. Thus the rim portion of the head 13 is flanged outwardly and then inwardly bent as indicated at 14 to form a channel into which is sprung a circular portion 15 of an approximately conical wire spring member 16 which extends upwardly and inwardly from said circular portion in a substantial spiral and terminally forms a loop 17 beneath the head of the screw 12. From said loop an end portion 18 of said wire extends through the slot of the screw head whereby the spring is adapted to rotatively drive the screw. The circular portion of said spring is snapped into the channel 13 of the cap under sufficient pressure to insure a rotation of the spring with said cap. Thus said cap is adapted to turn the screw 12 into the strip 10 or other engaged member and at the same time may be sprung slightly out from the surface of said strip or member, as shown in Fig. 3, to permit ready insertion or withdrawal of a looped cord beneath said cap. As in the first described construction the cap 13 is marginally notched at 19 to accommodate said cord, and preferably an end portion 20 of the spring engages in said notch to further adapt the cap to drive the spring.

It is a feature of this form of the invention that the spring connection between the cap 13 and screw 12 permits said cap to be tilted when desired as indicated in dash lines in Fig. 4 to facilitate removal of the pull cord or replacement thereof. Thus the cord can be taken off for washing, mending or any other purpose and readily replaced without disturbing the screw 12.

In that form of the invention which is illustrated in Figs. 7 to 10 inclusive, 21 designates a sheet metal blank consisting of a circular portion 21 having an arm 22 projecting radially therefrom, slits 23 being extended into said blank from the margin thereon, one on each side of said arm and the latter being formed at its free end with an aperture 24.

After stamping out such blank the next step consists in securing a screw 25 in the aperture 24 with the head of said screw abutting said arm. This connection may be rigidly established by riveting, welding or in any other suitable manner (see Fig. 8).

By means of suitable dies the circular member 21 of the blank is now dished to form the cap illustrated in Fig. 9. To complete the construction the arm 22 is bent into the cap in proximity to the interior face thereof as indicated in Fig. 10, thereby locating the screw 25 in a substantial axial relation to the

cap. Finally the fastener is tempered so that the arm 22 may exercise the desired spring function and the outer face of the cap is nickelized or is otherwise provided with a finishing coating or lining.

The construction just described presents all the advantages derived from the invention as illustrated in Figs. 3 to 6 inclusive, and may be more economically produced. The arm 22 establishes a connection between the cap and screw which will permit the screw to be turned into a supporting window shade strip or other member through rotation of said cap, and said arm is furthermore sufficiently resilient to permit a temporary outward adjustment of the cap to facilitate insertion of a cord beneath the cap or its removal therefrom.

While it will be apparent that the illustrated embodiment of my invention here disclosed is well calculated to adequately fulfill the objects and advantages primarily stated, it is to be understood that the invention is susceptible to variation, modification and change within the spirit and scope of the subjoined claims.

What I claim is:

1. A fastener comprising a screw, a head dished to inclose an end portion of said screw, and means resiliently attaching said head to said screw.

2. A fastener comprising a screw having an integral head, a supplemental dished head having a central aperture to receive the screw head, and spring means mounting the dished head upon said shank adjacent to said integral head.

3. A fastener comprising a screw having a pointed end, a head dished to inclose the other end portion of said screw, said head being marginally inwardly flanged, and a spring member engaging said marginal flange within said dished head and engaging said shank adjacent to its other end.

4. A fastener comprising a headed shank, a supplemental head dished to inclose the outer portion of said shank and formed with a central opening to receive the shank head, and a spring engaging said screw adjacent to its integral head and engaging said dished head adjacent to the margin thereof.

5. A fastener comprising a shank pointed at one end and headed at the other, a supplemental head dished to inclose the outer portion of said shank and centrally apertured for the passage of said shank and formed adjacent to its margin with an abutment, and a spring, mounting said supplemental head upon said shank, having a central portion looped about the shank adjacent to the head thereof and having end portions engaging said abutment.

6. A fastener comprising a substantially pointed support, and a cap dished to inclose the other end portion of said support, and

means resiliently connecting said cap and supporting member.

7. A fastener comprising an insert substantially pointed at one end, of a dished cap for surrounding and concealing the other end portion of said insert, and spring means carried by said insert for mounting said cap in substantially axial registration with said insert.

10. A fastener comprising an insert substantially pointed at one end, a dished cap for surrounding and concealing the other end portion of said insert, said cap having a flexible integral portion attaching it to said insert.

15. A fastener comprising an insert substantially pointed at one end, and a cap dished to surround and conceal the other end portion of said insert, said cap having an arm 20 integrally extending from a marginal portion thereof, and establishing the cap in a substantially axial registration with said insert.

25. A fastener comprising an insert substantially pointed at one end, and a cap dished to substantially surround and conceal the other end portion of said insert, said cap having a resilient arm extending thereto from its rim portion and rigidly connected to 30 said insert establishing the cap in substantial axial registration with the insert, a portion of said arm being struck out of the margin of the cap and forming an opening through which an element engaging said insert may 35 pass.

11. A fastener comprising a screw, a head dished to enclose a portion of said screw, and formed separately from the screw, and a resilient actuating connection from said head to 40 said screw.

12. A fastener comprising a screw, a head formed separately from said screw, and an actuating connection from said head to said screw, normally maintaining a coaxial relation between the head and screw, and affording the head a tilting movement relative to the screw.

13. A fastener comprising a screw, a dished head, and a spring lying completely 50 within said head, establishing an actuating connection from said head to said screw, and normally maintaining the head coaxial with the screw, while affording the head a tilting movement relative to the screw.

55. A fastener comprising a pointed insert, a head dished to enclose the portion of said insert remote from its point and formed separately from said insert, and a spring lying completely within said head normally maintaining said head coaxial with said insert and affording said head a limited tilting movement relative to the insert.

15. In a device of the character described, the combination with a fastener comprising 60 a dished head having a notched periphery

and a threaded shank axially carried by said head, of a pull cord looped around said shank and thereby adapted to be attached by said fastener to a support, said cord being engageable in the notch of said head for effecting a rotation of said fastener to screw its shank into said support.

In testimony whereof I sign this specification.

GLENN A. HIGBEE.
